UNITED STATES PATENT OFFICE.

MARTIN A. POND, OF BRISTOL, CONNECTICUT, ASSIGNOR TO STANDARD CARRIER COMPANY, OF SOUTHBURY, CONNECTICUT; A STATUTE CORPORATION OF CONNECTICUT.

CASH-CARRIER BOX.

1,346,676.

Specification of Letters Patent. Patented July 13, 1920.

Application filed December 1, 1919. Serial No. 341,743.

To all whom it may concern:

Be it known that I, MARTIN A. POND, citizen of the United States, residing at Bristol, in the county of Hartford and State of Connecticut, have invented a new and useful Improvement in Cash-Carrier Boxes, of which the following is a specification.

This invention relates to the cable gripping means of cash carrier boxes of the type which have a metallic cash and check box proper with an upper plate of sound insulating material, a lower plate of metal and an intervening block of sound insulating material secured to the bottom of the box for guiding it between the two rails of the track, and a fixed catch member and oscillating catch member for gripping the carrying cable that runs continuously adjacent to the track.

The object of the invention is to provide a gripping means for boxes of this character, which is cheap to construct, durable in use, easy to repair, and efficient in operation, and which will not occupy any space in the box proper.

This object is attained by pivoting the oscillatory catch member on a stud that is secured to and extends upwardly from the lower metallic guide plate through which the oscillatory catch member projects, and engaging the end of the oscillatory catch member which is adapted to swing toward and from the fixed catch member that is secured to the bottom of the box proper and projects downward through the lower guide plate, by the free end of a wire spring which is arranged to throw and retain the oscillatory catch member at both limits of its movement and is coiled about a stud that extends upward from the lower guide plate.

In the accompanying drawings Figure 1 shows a bottom view of a cash carrier box that embodies the invention. Fig. 2 is a side elevation of the same. Fig. 3 is an end view with a portion broken away on the plane indicated by the dotted line 3-3 on Fig. 4. Fig. 4 shows a horizontal section on the plane indicated by the dotted line 4-4 on Fig. 2. Fig. 5 is a side view of the oscillating catch member.

The receptacle 1 or box proper for containing the checks and cash to be transported, which may be any desired size and convenient outline, preferably oblong, is

usually pressed to shape from sheet metal. Beneath the bottom 2 of the box is the upper guide plate 3 that is somewhat wider than the box and is made of fiber or similar wear-resisting and sound-deadening material. The lower guide plate 4 is made of sheet metal with wings 5 that project outward from each side. Between the upper and lower plates is a spacing block 6 which is desirably made of fiber or a like noiseless substance. This block is somewhat narrower than the upper guide plate and with the side edges of the upper guide plate and wings of the lower guide plate provides the guideways 7 for the track rails upon which the carrier travels. These parts are fastened together and secured to the bottom of the box by screws 8.

The fixed catch member 9 extends through the guide plates and spacing block and has its foot 10 fastened to the under side of the bottom of the box proper. The oscillating catch member has a gripping finger 11 that projects downward through the lower guide plate from the end of a rocker arm 12. The hub 13 of the rocker arm is fitted upon a stud 14, one end of which is riveted to the lower guide plate while the other end extends up into a hole in the bottom of the box proper. Projecting up from the swinging end of the rocker arm is a headed pin 15. One end of the wire spring 16 for throwing and retaining the oscillatory catch plate at the limits of its movement is coiled about a stud 17 which is riveted to the lower guide plate. The free end of the spring is engaged with the headed pin 15 on the rocker arm.

This form of spring arranged as described is resilient and not liable to break, yet it is sure in action and firm in its pressure. It is cheap to provide and place in position and in case one should become broken another can be readily substituted. When the oscillatory catch member is pushed inward for gripping the carrying cable between it and the fixed catch plate, the spring throws the member quickly and holds it firmly, and yet, when the end of the track is reached and the oscillatory catch member is engaged with the trip the spring yields easily and permits a ready release of the carrier from the cable. This cable gripping means occupies no space in the box proper but is ap-

plied to the under side of the box in such manner that it may be easily repaired when necessary.

The invention claimed is:—

- 5 1. A cash carrier box comprising a receptacle, a supplemental bottom secured to the bottom of the receptacle and providing a track guide at its edges, a fixed cable gripping member projecting below said supplemental bottom, a stud fixed in said supplemental bottom, an oscillatory cable gripping member pivotally mounted on said stud and projecting below said supplemental bottom, and a spring in said supplemental bottom and engaging the oscillatory cable gripping member.
- 10 2. A cash carrier box comprising a receptacle, a supplemental bottom secured to the bottom of the receptacle and providing a track guide at its edges, a fixed cable gripping member projecting below said supplemental bottom, a stud fixed in said supplemental bottom, an oscillatory cable gripping member pivotally mounted on said stud and projecting below said supplemental bottom, and a coil spring held in said supplemental bottom and having its free end engaging the oscillatory cable gripping member.
- 15 3. A cash carrier box comprising a receptacle, a supplemental bottom secured to the bottom of the receptacle and providing a track guide at its edges, a fixed cable gripping member projecting below said supplemental bottom, a stud fixed in said supplemental bottom, an oscillatory cable gripping member pivotally mounted on said stud and projecting below said supplemental bottom, a stud fixed in said supplemental bottom, and a spring coiled about said last named
- 20 4. A cash carrier box comprising a receptacle, a supplemental bottom secured to the bottom of the receptacle and providing a track guide at its edges, a fixed cable gripping member secured to the bottom of the receptacle and projecting downward through the supplemental bottom, a stud fixed in said supplemental bottom, an oscillatory cable gripping member pivotally mounted on said stud and projecting below said supplemental bottom, and a coil spring in said supplemental bottom and engaging the oscillatory cable gripping member.
- 25 5. In a cash carrier box the combination with a receptacle of a supplemental bottom comprising an upper plate, a lower plate and a spacing block, secured to the bottom of the receptacle, a fixed cable gripping member secured to the receptacle bottom and projecting through the supplemental bottom, a stud fixed to the lower plate, an oscillatory cable gripping member pivotally mounted on said stud and projecting downward beyond the lower plate, a stud fixed to the lower plate and projecting upward in the supplemental bottom, and a wire spring coiled about said last named stud and having its free end engaging the oscillatory cable gripping member.
- 30 6. In a cash carrier box the combination with a receptacle of a supplemental bottom comprising a fiber upper guide plate, a metal lower guide plate and a fiber spacing block, secured to the bottom of the receptacle, a fixed cable gripping member projecting downward beyond said supplemental bottom a stud fixed in said supplemental bottom, an oscillatory cable gripping member pivotally mounted on said stud and projecting downward beyond said supplemental bottom, and a coil spring in said supplemental bottom and engaging the oscillatory cable gripping member.
- 35 7. In a cash carrier box the combination with a receptacle of a supplemental bottom comprising an upper guide plate, a lower guide plate and a spacing block, secured to the bottom of the receptacle, a fixed cable gripping member secured to the receptacle bottom and projecting through the supplemental bottom, a stud fixed to the lower guide plate, an oscillatory cable gripping member pivotally mounted on said stud and projecting downward beyond the lower guide plate, a stud fixed to the lower plate and projecting upward in the supplemental bottom, and a wire spring coiled about said last named stud and having its free end engaging the oscillatory cable gripping member.
- 40 8. In a cash carrier box the combination with a metal receptacle of a supplemental bottom comprising a fiber upper guide plate, a metal lower guide plate and a fiber spacing block, secured to the bottom of the receptacle, a fixed cable gripping member secured to the receptacle bottom and projecting through the supplemental bottom, a stud fixed to the metal guide plate, an oscillatory cable gripping member pivotally mounted on said stud and projecting downward through the metal guide plate, a stud fixed to the metal guide plate, and a wire spring coiled about said last named stud and having its free end engaging the oscillatory cable gripping member.

receptacle, a fixed cable gripping member projecting downward beyond said supplemental bottom, a stud fixed in said supplemental bottom, an oscillatory cable gripping member pivotally mounted on said stud and projecting downward beyond said supplemental bottom, and a coil spring in said supplemental bottom and engaging the oscillatory cable gripping member.

6. In a cash carrier box the combination with a receptacle of a supplemental bottom comprising a fiber upper guide plate, a metal lower guide plate and a fiber spacing block, secured to the bottom of the receptacle, a fixed cable gripping member projecting downward beyond said supplemental bottom a stud fixed in said supplemental bottom, an oscillatory cable gripping member pivotally mounted on said stud and projecting downward beyond said supplemental bottom, and a coil spring in said supplemental bottom and engaging the oscillatory cable gripping member.

7. In a cash carrier box the combination with a receptacle of a supplemental bottom comprising an upper guide plate, a lower guide plate and a spacing block, secured to the bottom of the receptacle, a fixed cable gripping member secured to the receptacle bottom and projecting through the supplemental bottom, a stud fixed to the lower guide plate, an oscillatory cable gripping member pivotally mounted on said stud and projecting downward beyond the lower guide plate, a stud fixed to the lower plate and projecting upward in the supplemental bottom, and a wire spring coiled about said last named stud and having its free end engaging the oscillatory cable gripping member.

8. In a cash carrier box the combination with a metal receptacle of a supplemental bottom comprising a fiber upper guide plate, a metal lower guide plate and a fiber spacing block, secured to the bottom of the receptacle, a fixed cable gripping member secured to the receptacle bottom and projecting through the supplemental bottom, a stud fixed to the metal guide plate, an oscillatory cable gripping member pivotally mounted on said stud and projecting downward through the metal guide plate, a stud fixed to the metal guide plate, and a wire spring coiled about said last named stud and having its free end engaging the oscillatory cable gripping member.

MARTIN A. POND.
